ELECTRIC LAMP MAKING APPARATUS

Waldemar P. Schoenoff, Muskego, Wis., and Paul Vargo, Lyndhurst, Ohio, assignors to General Electric Company, a corporation of New York

Application April 29, 1957, Serial No. 655,854

4 Claims. (Cl. 49—2)

Our invention relates in general to apparatus for making electric lamps, and more particularly lamps of the sealed-beam type such as disclosed in U.S. Patent 2,148,314, issued February 24, 1939, to D. K. Wright, and assigned to the same assignee as the present invention. Still more particularly, our invention relates to methods and apparatus incorporating an aiming or focusing structure into a sealed-beam lamp, and is an improvement of the apparatus described and claimed in U.S. Patent 2,237,186, issued April 1, 1941, to F. J. Malloy, and U.S. Patent 2,334,123, issued November 9, 1943, to F. C. Perkins, both assigned to the same assignee as the instant application.

Electric lamps of the type disclosed in the above mentioned Wright patent comprise a pressed reflector section which supports a filament or other light source and has a definite interior optical shape, usually parabolic, with a reflecting coating thereon applied to redirect the light from the filament in a predetermined pattern. Over the mouth of the reflector section, which has the general form of a cup and constitutes one portion of the lamp bulb, is sealed another pressed glass cover or lens section constituting the other portion of the bulb and which is usually provided with light refracting media or panels for concentrating or diffusing the light in a definite pattern. The sealing together of the two glass sections is effected at their peripheral edges which are provided, for this purpose, with cooperating annular sealing surfaces.

In order to focus or aim such lamps it has heretofore been proposed to provide the lamp with one or more accurately locating reference shoulders or surfaces on the exterior of the lens section adjacent the peripheral seal portion thereof, which reference surfaces are adapted to be engaged by separate mechanical aiming devices. Such devices are especially useful when the lamp is installed on a vehicle. However, these reference surfaces on the lamp must be accurately located in a plane bearing a definite relation to the axial center line of the lamp as well as the axis of the reflecting surface of the lamp. Since the reflector section, the lens section and the filaments are all accurately located with respect to one another during manufacture, it is desirable to incorporate such reference surfaces on the lamp lens during manufacture of the lamp so that they will necessarily be accurately located with respect to the axial center line of the lamp and to the optical axis of the reflecting surface. Such reference surfaces afford a ready means for mechanically aiming the lamp while mounted in place on the vehicle.

To this end, the apparatus of the instant invention is provided with means to locate such aiming reference surfaces or bosses on the lamp lens during the course of manufacture of the lamp thereby eliminating the necessity for special finishing operations after assembly of the lamp parts.

It is an object of our invention to provide a novel apparatus for making an electric lamp of the above mentioned type having reference surfaces or bosses on the

exterior of the lens section thereof which are accurately formed and located during manufacture with respect to the axial center line of the lamp and to the axis of the reflector section thereof.

Another object of our invention is to provide new and improved apparatus for making an electric lamp with reference surfaces or bosses such as described above which may be incorporated on existing lamp-making equipment such as that disclosed in the above mentioned 10 Malloy Patent 2,237,186.

Still another object of our invention is to provide apparatus for making an electric lamp with reference surfaces or bosses of the type described which may be operated at high speed and with precision and reliability.

Briefly stated, in accordance with one aspect of our invention, the lens or cover glass section of an electric lamp of the above described character is preformed with a plurality of aiming bosses extending upwardly from the lens at points inwardly of the sealing flange of the lens. A sealing machine of the indexing carrier type, such as is conventionally employed to seal together the lens and reflector sections of a sealed-beam type lamp, is provided; at one of the work stations, with a heating means to soften the glass aiming bosses to a plastic condition. It is further provided with means to engage the aiming bosses when in a heated plastic state to deform them and shape the reference surfaces so that the surfaces are accurately located with respect to the axial center line of the lamp and the optical axis of the reflecting surface.

Further objects and advantages of the invention will appear from the following detailed description thereof and from the accompanying drawings wherein:

Fig. 1 is a diagrammatic plan view of a lamp sealing machine comprising the invention.

Fig. 2 is a vertical section through the turret of the sealing machine taken on the line 2—2 of Fig. 1.

Fig. 3 is a perspective view of a lamp made in accordance with the invention.

Fig. 4 is a perspective view of a section of a lamp showing seating and locating pads and part of the machine head in which the pads must rest.

Referring to Fig. 1, the apparatus shown therein is similar to that described and claimed in the above identified Malloy and Perkins patents, and comprises a rotatable carrier or turret 1 provided around its periphery with a plurality of heads 2 for supporting and carrying glass reflector sections 3 (Fig. 2) which are to be individually sealed to a cover glass or lens section 4 to form the envelope or bulb of the lamp. The heads 2 which themselves rotate on the turret, are adapted to support the glass reflector sections 3 in an upright position with their concave reflecting surfaces 5 facing upwardly. The turret 1 is rotatably mounted on a vertical central shaft or column 6 and it is intermittently indexed about the shaft 6 by suitable indexing means (not shown) of the conventional type to carry the assembled reflector and lamp sections 3 and 4 in each head 2 progressively to a succession of work stations A to Q where various operations not concerned with the instant invention are performed on the said assembled lamp sections.

As shown in Fig. 2 each head 2 comprises a ring-shaped main lamp holder 7 having a lamp seating rim 8 at its upper end provided with a plurality of flat seating surfaces 9 on which seating surfaces 10 of lamp orienting bosses 11 of the reflector section 3 are adapted to rest to support and orient the reflector section in the head. When the assembled lamp is installed in a vehicle a series of seating surfaces 10a on bosses 11a on the lamp section 3 serves as reference surfaces to properly seat the lamp with respect to the vehicle, while bosses 11 serve to orient the lamp about its own axis. While these surfaces 10a

may be used to orient and seat the lamp section 3 on the seating rim 8, it is preferable to use the seating surfaces 10 of bosses 11 to permit more clearance between the lamp section 3 and the seating rim 8, thereby facilitating the assembling operations performed at prior work stations. It is possible to use surfaces 10 rather than surfaces 10a for seating the lamp as surfaces 10 are accurately formed parallel to surfaces 10a.

The holder 7 is mounted on an upper bracket 12 supported by standards or posts 13 extending upwardly from a lower bracket 14 having a depending sleeve 15. The sleeve 15 extends through and is rotatively mounted in a bearing 16 on the turret 1, a ball bearing 17 being interposed between the underside of the bracket 14 and the upper end of the turret bearing 16 to thereby support, and permit free and easy rotation of the head 2 on the turret. The heads 2 are rotated, at each station around the machine except the loading and unloading stations A and Q, and the boss surface forming station P, by means of a pulley 18 fastened to the lower end of the sleeve 15 and engaged by a moving belt 19. The head 2 is restrained from rotation or movement at stations A, P and Q by the engagement of a pin 20, which is secured to pulley 18, with a track 21.

Extending through and vertically movable in the sleeve 15 but rotatively interlocked therewith so as to rotate as a unit with said sleeve, is a hollow spindle or inner sleeve 22. At its upper end, the spindle 22 is provided with a secondary support or holder 23 for the reflector section 3, the said secondary holder having openings 24 which receive the customary metal filament terminal thimbles or ferrules 25 on the reflector section. Engagement of the thimbles 25 with the openings 24 positively prevents relative rotation between the holder 23 and the reflector section 3. The lower end of the spindle 22 is provided with a shoe 27 which, during rotation of the turret 1 and consequent movement of the respective heads 2 in a circular path around the machine, rides on the upper surface of a cam track 28 extending vertically around the machine and supported from a stationary part of the machine. The shoe 27 is provided with an aperture 29 extending therethrough from its undersurface and communicating with the hollow interior of the spindle 22 and inner sleeve 26. When the head 2 is positioned at different stations around the machine, the aperture 29 in the shoe 27 aligns with different ports (not shown) in the cam track 28 at such stations, different ones of said ports being connected to a source of inert or reducing gas for lamp flushing purposes, to a source of vacuum, or to a source of inert or reducing gas under pressure, depending upon the particular operation which is to take place at each station.

As shown in Fig. 3, the lens reflector section 3 is provided with a sealing flange 30 around the periphery thereof of which mates with a corresponding sealing flange 31 formed as part of the lens section 4. Proper mating of the parts is assured by cooperating recesses and projections on the flanges (not shown) which means that the lens section 4 will be properly positioned with respect to the lamp filaments. In addition, the lens section is provided with a plurality of upstanding reference surfaces or bosses 32 which are molded integrally with the glass lens section at the time of its manufacture and which are located at spaced intervals around the flange in predetermined position with respect to the bosses 11 when the lens section and reflector section are assembled together. Three of such reference surfaces or bosses will provide a sufficient number to give a proper reference plane for the mechanical aiming device previously mentioned. Until such time as the lens section 4 is united or fused to the reflector section 3 to form the complete lamp bulb assembly, it is not possible to predetermine the exact lengths or proper orientation of the ends of the bosses 32 so that they may be used with the aiming

device. This step in the manufacture of the lamp will be described later.

At the first or loading station A of the machine, a lamp reflector section 3 and a lens glass section 4 are assembled together and placed on the secondary holder 23 of the head 2 so as to rotate with the head. At this station the holder 23 is in an elevated position with respect to the ring-shaped main holder 7 because of the engagement of shoe 27 at the lower end of the spindle 22 with an elevated portion of the cam track 28. This means that the thimbles 25 are seated in openings 24 to orient the lamp assembly on the holders 23; since at this position pin 20 engages track 21 the result is that the lens structure and aiming bosses 32 are properly oriented for all subsequent operations as the assembly is indexed around the turret. Turret 1 then indexes the head 2 with the assembled reflector and cover glass sections 3 and 4 thereon progressively through stations B through O where the flanges 30 and 31 of the glass sections 3 and 4 are heated, rolled and sealed essentially as described in the above identified Perkins Patent 2,334,123.

In accordance with the instant invention, and in order to fix the exact lengths and proper orientation of the ends of the bosses 32 so that they may be used for cooperation with the aiming device, the turret is provided at station P with means to heat the bosses to a plastic state and then deform or displace them to provide the proper reference surfaces for engagement with the device. To this end, the apparatus is provided with a burner structure 33 shown at the top of Fig. 2. Heating gas is supplied through a burner inlet 34 and passes through a manifold 35 forming part of the burner structure 33, there to be directed at the upper portions of the aiming bosses 32 by a plurality of nozzles 36. The burner structure 33 slides vertically upon spaced pins 37, being restrained in its lower position by the engagement of pin head 38 with a surface 39 of the burner structure. The burners 36 may be adjusted vertically to proper position to direct the gas flame against the bosses 32 by adjustment of a plurality of set screws 40. During operation the set screws rest on the glass lens section 4 while the aiming bosses 32 are being heated.

Suitable displacement means 41 is also provided at station P for determining the exact lengths of the bosses 32 and for properly orienting their upper surfaces 42 relative to the reflector section 3 so that the bosses will cooperate properly with the aiming device. As shown in Fig. 2, the said displacement means 41 comprises a supporting frame 43 overlying the main holder 7 and the lamp envelope at station P and is provided with three depending dies 44 having flat under surfaces 45 disposed approximately in a horizontal plane and adapted to engage the initially rounded tops of the aiming bosses 32, as shown by the dotted line 46. The supporting frame 43 is carried by a support arm 47 overhanging the periphery of the turret 1 and fastened to the upper end of a vertically extended operating rod 48. The operating rod 48 is mounted for vertical reciprocating movement in a stationary support or bearing 49.

Rod 48 is vertically reciprocated in timed relation to the indexing movements of the turret 1, e.g., operating from the main cam shaft of the machine. A cam 50 which is operated from the main cam shaft, imparts essentially vertical motion to a follower roller 51 which, in turn, rocks lever 52 about its stationary pivot 53. A pin 54 at the lower end of rod 48 rides in a slot 55 formed at the end of lever 52 so that as the lever rides about its pivot, vertical movement is imparted to rod 48. The reciprocating vertical movement of operating rod 48 imparts periodic reciprocal vertical movement to the displacement means 41 in such a manner that the displacement means 41 and the burner structure 33 suspended therefrom are raised during indexing of the turret 1 and are lowered to an operative position when the

indexing of the machine is complete. Burner structure 33 follows upward vertical movement of frame 43 because pins 37 are mounted in the frame and the pin ends 38 engage surface 39 to lift the burner structure out of engagement with the lens section upon indexing of the turret. A group of stop pins 56 is located on the support frame 43 outwardly of and spaced more or less equally around and concentric with the annular stop dies 44 thereon so as to just clear the outer periphery of the seating rim 8 on the lamp holder ring 7 when the displacement means 41 is vertically aligned therewith and located at its lowered operative position. As shown, the stop pins 56 are vertically adjustable in the support frame 43 so that they can be adjusted to locate the under surface 45 of the dies 44 in the desired predetermined relation, e.g. in parallel relation to the seating surfaces 9 of the holder ring 7 when the displacement means 41 is at its lowered operative position with the stop pins 56 in engagement with an annular flange 57 on the holder ring 7.

The lowering of the displacement means 41 into an operative position, after the upper portions 46 of the aiming bosses 32 have been heated to plastic states by the burner 33, brings the under surfaces 45 of the dies 44 into contact with the aiming bosses 32 thereby pressing and deforming the upper portion of the aiming bosses 32 to the position represented by the upper surface 42. The exact vertical alignment of the dies in relation to the main lamp holder 7 is accomplished by the adjustment of the stop pins 56 so that the upper surface 42 of the aiming bosses 32 is held in precise and accurate relation to the seating surfaces 10 on the under side of the lamp bulb. This means that the reference surfaces or outer ends of the bosses 32 will be accurately located with respect to the lamp filaments, the reflector and the axial center line of the lamp.

In operation, the cam 50 is so constructed as to have the displacement means 41 and the burner 33 in a raised position during indexing of the turret 1. After the head 2 has moved into position at station P the operating rod 48 moves downwardly a sufficient distance to permit the set screws 40 on the burner structure 33 to contact the lens section 4 of the lamp, the burner 33 thereby having nozzles 36 properly aligned to adequately heat the upper portion of the aiming bosses 32. Upon continued downward movement of operating rod 48, the burner 33 remains stationary due to the disengagement of the pin heads 38 with surface 39 of the burner 33. This continued downward movement of the operating rod 48 then causes the dies 44 to engage the heated bosses 32 to accurately form and locate the upper surfaces 42 of the aiming bosses 32 as described above.

To permit the engagement of all the stop pins 56 with the flange 57 on the main holder ring 7 when the displacement means 41 is lowered to its operative position, thereby insuring the proper plane positioning of the under-surfaces 45 of the dies 44 in exact predetermined relation to, e.g. parallel with the reflector section seating surfaces 9, the displacement means 41 is supported on the support arm 47 by a suitable connection 58 which allows a limited amount of rocking movement of the control means 41 and preferably, in addition, a limited amount of lateral shifting movement as well. To lock the operating rod 48 against rotation within the bearing 49 so as to prevent swinging movement of the support arm 47 about the bearing and thereby maintain hanger post 59 of the displacement means 41 in true vertical alignment with the holder ring 7 of each head 2 when positioned at station P, the operating rod 48 is provided with a cross-pin 60 which snugly fits and slides up and down within a vertical slot 61 in the bearing 49. To prevent rotation of post 59 in the support arm 47, a key 62 is secured to post 59 and slidably engages a keyway in arm 47.

While we have described certain preferred embodiments of our invention by way of illustration, many modi-

fications will occur to those skilled in the art and a number of equivalents may be substituted. We, therefore, wish to have it understood that we intend in the appended Claims to cover all such modifications as fall within the true spirit and scope of our invention.

What we claim as new and desire to secure by Letters Patent of the United States is:

1. An apparatus for locating lamp aiming reference surfaces on bosses upstanding from a lamp envelope, a holder for supporting the lamp envelope, said holder being provided with a stop flange, a supporting frame movable toward and away from the holder, a burner structure carried by said supporting frame, said burner structure being provided with heating nozzles and with means for engaging the lamp envelope as the supporting frame is moved toward the holder to locate such heating nozzles in position to direct a heating flame against the lamp bosses, die means carried by said supporting frame for engaging the heated bosses to deform them as the frame moves toward the holder, and stop means carried by said supporting frame for engaging said stop flange to limit movement of said frame toward said holder.

2. An apparatus for locating lamp-aiming reference surfaces on bosses upstanding from a lamp envelope, a holder for supporting the lamp envelope, said holder being provided with a stop flange, a supporting frame movable toward and away from the holder, a burner structure, means for supporting said burner structure on said supporting frame for movement with respect to said frame, said burner structure being provided with heating nozzles and with means for engaging the lamp envelope as the supporting frame is moved toward the holder to limit movement of said burner structure to bring said nozzles into position to direct a heating flame against the lamp bosses, die means carried by said supporting frame for engaging the heated bosses to deform them upon further movement of the frame toward the holder, and stop means carried by said supporting frame for engaging said stop flange to limit movement of said frame toward said holder.

3. An apparatus for locating lamp-aiming reference surfaces on bosses upstanding from a lamp envelope, a holder for supporting the lamp envelope, a supporting frame movable toward and away from the holder, a burner structure carried by said supporting frame, said burner structure being provided with heating nozzles and with means for engaging the lamp envelope as the supporting frame is moved toward the holder to locate said heating nozzles in position to direct a heating flame against the lamp bosses, die means carried by said supporting frame for engaging the heated bosses to deform them as the frame moves toward the holder, and cooperating means on said holder and frame for limiting movement of said frame toward said holder.

4. Apparatus for forming lamp-aiming surfaces on a cover glass section of a lamp envelope, said lamp envelope including a reflector section and a cover glass section having bosses integral therewith for the formation of said lamp-aiming surfaces, said apparatus comprising, in combination, a ring-shaped holder for the reflector and cover glass sections disposed with its axis vertical and having a seating rim at its upper end provided with a flat horizontally disposed upwardly facing annular seating surface for supporting the reflector section with its concave reflecting surface facing upwardly, said holder means also having stop flange means extending horizontally outward from the holder ring below and outwardly beyond the seating rim thereon, a burner structure for heating the bosses to a plastic state and adapted to move vertically downward to engage the cover glass section of the lamp envelope and including flame directing nozzles in heating relation to the bosses, glass-forming dies adapted to be moved vertically downward over the bosses while in the heated plastic state so as to deform the

upper edge of the bosses into lamp-aiming surfaces which lie in a predetermined transverse plane relative to the axis of the envelope, displacement means mounting said die members for limited vertical movement, connecting means secured to said displacement means for vertically moving the displacement means and associated die member, stop pins extending downwardly from said displacement means at approximately equally spaced points about and located outwardly of the lamp envelope, said stop pins being engagable with the said stop flange on the holder ring on downward movement of the stop member to thereby accurately locate the dies in a predetermined position relative to said holder ring with the die members accurately disposed in a plane parallel to and spaced a

predetermined distance upwardly from the plane of the reflector seating surface on said holder ring.
